LEASE FORMING MACHINE

Simpson James Adams, Greenville, S. C.

Application April 25, 1936, Serial No. 76,463

12 Claims. (Cl. 28—40)

This invention relates to a machine for forming an end-and-end lease in warp, and in particular to a machine for forming a lease in warp having a large number of ends per inch. The present invention involves improvements over 5 the arrangement disclosed in my pending application Serial No. 16,250, filed April 13, 1935.

In my earlier filed application I have disclosed an arrangement for forming an end-and-end lease in warp having a large number of ends per 10 inch, the arrangement involving a special reed construction in which each split or dent in the reed is provided with a plurality of spaced hook elements, and the warp to be leased is guided through the reed in four or more superposed vertically spaced sheets, with each reed space receiving an end from each sheet. Split rods (or parting bars) are suitably positioned to guide the sheets of warp through the reed so that two 15 sheets are arranged between each pair of hooks. Suitable means is provided for shifting the reed both horizontally and vertically to selectively engage the ends of one or the other of the two sheets located immediately above each hook, and to carry the engaged ends vertically beyond the 20 unhooked ends to form a shed between the hooked ends and the unhooked ends.

Broadly, the object of the present invention is to devise an arrangement to facilitate the 25 operation of the leasing device disclosed in my prior application.

A specific object of the present invention is to provide a movable support for the split-rods which hold the warp sheets in vertically spaced 30 relation, and to provide an arrangement for shifting the split-rod support along the bed of the machine to a point adjacent the reed when it is desired to shift the reed to engage the warp ends so the warp ends will be accurately positioned with respect to the hooks on the reed, and, 35 after the warp ends have been engaged, to quickly shift the split-rod support away from the reed to allow the reed to be moved vertically to form a shed in the warp. My invention also involves a 40 method of manipulating the arrangement to form a lease.

A preferred embodiment of my invention is illustrated in the accompanying drawings, in which:

50 Figure 1 is a fragmentary view showing the essential elements of my invention in side elevation, with the split-rod support moved away from the reed support;

55 Figure 2 is a fragmentary side elevational view like Figure 1, except that the split-rod support

has been moved into position adjacent the reed support;

Figure 3 is an enlarged fragmentary view taken along line 3—3 of Figure 1;

Figure 4 is a fragmentary side elevational view 5 like Figure 1 showing the reed in elevated position to form a shed in the warp;

Figure 5 is a sectional view taken along line 5—5 of Figure 1; and

Figure 6 is an enlarged view showing certain 10 details of construction of the split-rod support.

For the purpose of illustration, I shall describe my invention as applied to a slasher, but it will be understood that my lease forming machine may be used independently of a slasher, and in 15 any situation where it is desired to form an end-and-end lease in warp. Referring to Figure 1, 1 indicates a section of the top side beam of the slasher frame located between the steam cylinder and the extensible comb on the slasher. A similar side-beam 1a is located in the opposite side 20 of the slasher as shown in Figure 5. The steam cylinder is not shown, but it is located to the right of Figure 1, and the extensible comb, the presser roll, the delivery roll and the warp beam 25 are all located to the left of Figure 1 and are not shown.

The special hook reed for forming the lease is shown in end elevation at 2 and is mounted in vertical position transversely of the slasher 30 frame. The details of construction of the reed 2 are given in my copending application above referred to and will not be described here. It will suffice to say that the reed is of the open-top type consisting of a plurality of splits supported from 35 a rigid back, each split being provided with a plurality of hook elements spaced along the length thereof, and the hooks are arranged to engage warp ends bearing against the supporting split but will pass warp ends bearing against 40 the adjacent split. Rigid end-bars are supported from the back and provide lateral support for the splits. In Figure 2, I have shown the end bar of the reed broken away to illustrate the spaced 45 hooks 2a on one split of the reed.

The arrangement for shifting the reed transversely of the warp sheets consists of two vertical frames, one shiftable horizontally and the other mounted on the first and being shiftable vertically. The horizontally shiftable frame is formed 50 of two end members 3 slidably mounted upon a cross-beam 4 supported between side beams 1 and 1a. The end members 3 are joined by horizontal rods (not shown) extending between these members transversely of the slasher frame. One 55

end member 3 is provided with a toothed rack 3a extending transversely of the side beam 1, and the horizontally slideable frame is shiftable transversely of the slasher frame by means of a sector gear 5 engaging the rack 3a, the gear 5 being mounted upon a stub shaft 6 journaled in brackets 7 and 8 secured to the side beam 1. The gear 5 is operated by lever 9 secured to the end of shaft 6. A short rod 3b secured to end-member 10 3 extends transversely of the slasher frame and passes through a hole in a flange 8a on bracket 8 with a slight clearance to permit sliding of the rod in the hole. A similar rod is provided at the other end of the frame for the lateral support of 15 the frame and to maintain it in vertical position. The vertically shiftable frame is mounted to slide vertically within the horizontally slideable frame and is formed of two end members 10 joined by suitable horizontal rods (not shown) extending 20 transversely of the slasher frame. One face of the end members 10 is provided with a gear rack at the upper end and the frame is raised and lowered by means of spur gears (not shown) engaging these racks and mounted upon shaft 11 which may be rotated by the handwheel 12. The 25 reed 2 is supported from the vertically sliding frame by any suitable brackets engaging the end bars of the reed, such as brackets 13 and 14. From the foregoing, it will be seen that the reed 30 2 may be moved vertically by operation of the handwheel 12 and horizontally by operation of the lever 9. My copending application above identified discloses an arrangement for operating the reed substantially like that disclosed herein 35 and differing only in details of construction.

The split-rod support for vertically spacing the sheets of warp passing through the reed is shown to the right of the reed support in Figure 1. This support consists of two inverted gear racks 15 40 and 15a mounted longitudinally of the two side-beams 1 and 1a (see Figures 1 and 5), and two base elements 16 and 16a having H-shaped sections (as shown in Figure 5) are arranged to slide upon racks 15 and 15a respectively. A shaft 45 at 17 is journaled in the lower portion of base elements 16 and 16a and two spur gears 18 and 18a located in the lower bifurcations of the two base members, respectively, and engaging the racks 15 and 15a, are secured to the shaft 17 and 50 are driven by handwheel 19 mounted on one end of the shaft 17. Two horizontal shafts 20 and 21 are journaled in the upper portion of base members 15 and 15a. Two arms or standards 22 and 23 are secured to the shafts 20 and 21 within the 55 upper bifurcation of base member 16, and the lower ends of these arms are provided with inter-engaging sector gears which cause the two arms to move symmetrically with respect to the vertical axis of the base 16. A similar pair of arms 60 22a and 23a are likewise secured to the other ends of shafts 20 and 21 within the upper bifurcation of the base member 16a. The shaft 21 is extended at one end beyond the base member 16 and is provided with an operating lever 24 by 65 which the standards 22-23 and 22a-23a may be moved into the vertical position shown in solid lines in Figure 1, or into an angular position shown in dotted lines in Figure 1 for the purpose to be described hereinafter. Suitable straps 25 70 and 25a may be provided for maintaining the standards in vertical position, but these straps are removed when it is desired to open the standards.

Each of the standards on the split-rod support is provided with a plurality of collar elements 26

which may be adjustably clamped in any desired position along the length thereof by means of set screws 27, and each collar is provided with a transverse bore for receiving the reduced end of a parting bar or split-rod 28. By supporting the 5 split-rod 28 transversely of the slasher frame by means of the vertically adjustable collars 26, it is possible to quickly and easily adjust the vertical spacing between the sheets of warp passing through the slasher. By supporting half of the 10 split rods from one standard and half from the other standard, it is possible to obtain a very close vertical spacing between the warp sheets.

In the drawings, I have illustrated my split-rod support for guiding six warp sheets, A to F 15 inclusive, through the slasher in vertically spaced relation, but additional sheets may be accommodated by adding more split-rods. It will be understood that the warp sheets are supplied from the creel at the back of the slasher, and 20 are passed through the sizing vat and over the steam cylinder, through the split-rod support, through the leasing reed, and through the remainder of the slasher. In first setting up the slasher, the sheets of warp are first roughly positioned in the split-rod support, each sheet being supported by an individual split rod. In order to accurately adjust the vertical spacing of the split-rods, the reed 2 is moved to its lowermost position and the split-rod support is moved 25 into position adjacent the reed support as shown in Figure 2. The split-rods are then adjusted in position on the supporting standards so that two sheets of warp are located immediately above each row of hooks on the reed, as shown in Figure 2. It will be seen that the ends of sheets 30 A and B are positioned immediately above the lowermost row of hooks, the ends of sheets C and D are positioned immediately above the second row and the ends of sheets E and F are 35 positioned immediately above the third row of hooks. If additional sheets are being run through the slasher they will be positioned in a like manner above the extra rows of hooks. When the warp sheets are arranged as described, it is 40 possible, by shifting the reed horizontally and vertically to simultaneously select the ends of either the odd numbered sheets or the even numbered sheets as desired, and, by shifting the reed so that the hooks will pass the unhooked ends, 45 the hooked ends may be moved vertically beyond the unhooked ends to form a shed between the odd numbered sheets and the even numbered sheets. 50

The position of the split-rod support for the 55 normal running of the slasher is shown in Figure 1, and where a small number of sheets are being passed through the slasher, the split-rod standards may remain in vertical position as shown in solid lines, but where a large number 60 of sheets are employed, the split-rod standards may be opened up as shown in dotted lines in Figure 1 in order to relieve the tension on the warp sheets as they are being drawn through the slasher. If a large number of sheets are being 65 used and the standards are allowed to remain in vertical position, the uppermost sheets would be subjected to greater tension than the lowermost sheets, but by opening the standards, the tension is more or less equalized.

When the warp beam becomes full and is ready to doff, an end-and-end lease must be formed in the warp before the warp is cut. In order to form the lease, the reed is moved to its lowermost position and the split-rod support is moved 70 75

to the position adjacent the reed support shown in Figure 2. The reed is then manipulated to engage the ends of the odd numbered or the even numbered sheets, for example, the ends of the even numbered sheets B, D and F are engaged. The reed is then shifted so the unhooked ends bear against adjacent splits and will pass the hooks. The split-rod support is then moved away from the reed support as shown in Figure 4, and the reed is then shifted to carry these sheets vertically upward and beyond the odd numbered sheets to a position shown in Figure 4. A leasing bar 29 is then inserted within the shed formed between the odd numbered sheets and even numbered sheets as shown in Figure 4. The leasing bar 29 is then moved to a position adjacent the extensible comb and a leasing string is inserted in the shed in front of the comb and the bar 29 is removed. In forming the second 20 shed of the lease, the reed is returned to its lowermost position so that the warp sheets again occupy the normal running position shown in Figure 1, and then the same series of operations are performed as described above for forming 25 the first shed except that the ends of sheets A, C and E are engaged and are raised above sheets B, D and F. The leasing string is then returned through the second shed at the front of the comb and the end-and-end lease is complete.

From the foregoing, it will be seen that by providing a slidable support for the split-rods, it is possible to accurately and quickly position the warp sheets with respect to the hooks on the leasing reed simply by moving the split-rod support to a position adjacent the reed support, and after the reed has been manipulated to engage the ends of the desired sheets, the split-rod support is moved away from the reed support 40 in order to allow the engaged ends to be raised to form a shed without subjecting the engaged ends to excessive tension.

Many modifications of my invention will be obvious to those skilled in the art. For example, the base members 16 and 16a may be arranged to rest directly on the side frame members 1 and 1a and the racks 15 and 15a may be inverted and supported directly on the side-beams. Also, by increasing the vertical separation of the hooks on the reed or by decreasing the size of the split-rods, all of the split-rods may be supported on one set of standards and the other set can be eliminated.

What I claim is:

1. In combination, a leasing reed, a plurality of split-rods for guiding a plurality of sheets of warp through said reed in vertically spaced relation, a unitary carriage for supporting said split-rods parallel with said reed, and means for shifting said carriage towards and away from said reed while maintaining the split-rods parallel with the reed.

2. In combination, a leasing reed provided with hook elements on the splits, a plurality of split rods for guiding a plurality of sheets of warp through said reed in vertically spaced relation, a unitary support for said split-rods, and means for shifting said support towards and away from said reed in a direction parallel with said warp sheets.

3. In combination, a leasing reed provided with a horizontal row of hook elements supported on the splits thereof, each split being provided with one hook element in said row, a plurality of split-rods for guiding a plurality of sheets of warp

through said reed in vertically spaced relation, a unitary carriage for supporting said split-rods in vertically spaced relation parallel with said reed, and means for shifting said carriage towards and away from said reed while maintaining the split-rods parallel with the reed. 5

4. In combination, a leasing reed provided with a plurality of horizontal rows of hook elements supported on the splits thereof, each split being provided with one hook element located in each horizontal row of hooks, a plurality of split-rods for guiding a plurality of sheets of warp through said reed in vertically spaced relation, a unitary carriage for said split-rods, means for shifting said carriage from a position adjacent said reed 10 to a position removed from said reed, said carriage embodying means for the independent vertical adjustment of each split-rod on said carriage whereby said warp sheets may be accurately positioned with respect to the rows of hooks on 15 said reed when said carriage is in a position adjacent said reed.

5. In combination, a leasing reed provided with a plurality of horizontal rows of hook elements supported on the splits thereof, each split being 20 provided with one hook element located in each horizontal row of hooks, a plurality of split-rods for guiding a plurality of sheets of warp through said reed in vertically spaced relation, a unitary carriage for said split rods, means for shifting said carriage from a position adjacent said reed to a position removed from said reed, said carriage embodying means for the independent vertical adjustment of each split-rod on said carriage, and 25 means for shifting said reed transversely of said warp sheets both horizontally and vertically. 30

6. In combination, a leasing reed provided with a plurality of horizontal rows of hook elements supported on the splits thereof, each split being 35 provided with one hook element located in each horizontal row of hooks, a plurality of split rods for guiding at least four sheets of warp through said reed in vertically spaced relation with each reed space receiving one end from each sheet, a carriage located adjacent said reed for supporting said split-rods and embodying means providing for the independent vertical adjustment of each split-rod whereby two sheets of warp are positioned in vertical spaced relation above each 40 row of reed hooks, means for shifting said reed transversely of the warp sheets both horizontally and vertically to selectively engage the ends of one or the other of the pair of warp sheets located above each row of hook elements, and means for shifting said split-rod carriage away from said 45 reed to permit said reed to be raised to form a shed between the odd numbered and the even numbered sheets without subjecting the warp to excessive tension. 50

7. In a leasing machine, the combination of a 60 base frame having two parallel side beams, a leasing reed supported between said beams and in vertical position, a unitary carriage supported between said side-beams for supporting a plurality of split rods parallel with said reed and in 65 vertically spaced relation, and means for shifting said split rod carriage along said beams towards and away from said reed while maintaining the split rods parallel with the reed.

8. In a leasing machine, the combination of a 70 base frame having two parallel side-beams, a leasing reed supported between said beams and in vertical position, a carriage supported between said side-beams for supporting a plurality of split-rods parallel with said reed and in verti- 75

- cally spaced relation, and means for shifting said split-rod support towards and away from said reed while maintaining the split-rods parallel with the reed, said shifting means comprising a pair of gear racks supported on said side-beams, a shaft journaled on said split-rod support transversely of said side-beams and having spur gears mounted thereon meshing with said gear racks, and a handwheel for rotating said shaft.
10. A split-rod support comprising a base frame having two parallel side-beams, a carriage arranged transversely of said side-beams and including two vertical standards at the ends thereof, means for supporting a plurality of split-rods between said standards in horizontal position and in vertically spaced relation, said supporting means providing for the independent vertical adjustment of each split-rod on said standards, and means for shifting said carriage along said side-beams.
15. 9. A split-rod support comprising a base frame having two parallel side-beams, a carriage arranged transversely of said side-beams and including two vertical standards at the ends thereof, means for supporting a plurality of split-rods between said standards in horizontal position and in vertically spaced relation, said supporting means providing for the independent vertical adjustment of each split-rod on said standards, and means for shifting said carriage along said side-beams.
20. 10. A split-rod support comprising a base frame having two parallel side-beams, a carriage arranged transversely of said side-beams and including two base elements in slidable engagement with said side-beams, a vertical standard supported on each base element, a plurality of split-rods supported between said standards in horizontal position and in vertically spaced relation, a gear rack on each side-beam, a shaft journaled on said carriage and having mounted thereon a pair of spur gears meshing with said racks, and a handwheel for said shaft for operating said gears whereby said carriage may be shifted along said base frame.
25. 11. A split-rod support comprising a base frame having two parallel side-beams, a carriage arranged transversely of said side-beams and including two base elements in slidable engagement with said side-beams, a pair of standards pivotally supported on each base element, said standards being spaced along the major axis of said base frame and having their pivotal axes transversely thereof, each pair of standards being provided with inter-engaging sector gears whereby said standards maintain symmetrical positions with respect to a vertical plane, and at least two standards on opposite sides of said carriage being pivotally supported upon a shaft journaled on said carriage and provided with means for adjusting the angular position of said standards, a plurality of split-rods supported between each pair of opposing standards in horizontal position, a gear rack on each side-beam, a shaft journaled on said carriage and having mounted thereon a pair of spur gears meshing with said racks, and a handwheel for said shaft for operating said gears whereby said carriage may be shifted along said base frame.
30. 12. The method of manipulating the apparatus of claim 5 to form an end-and-end lease in the warp which consists in arranging the warp to pass through the reed in four or more even numbered sheets with each reed space receiving one end from each warp sheet, shifting the split-rod carriage to a position adjacent said reed, adjusting the vertical position of said split-rods to arrange two warp sheets in vertically spaced relation above each horizontal row of hook elements, shifting said reed both horizontally and vertically to engage the ends of either the odd numbered sheets or the even numbered sheets, shifting said reed horizontally so that the unhooked ends bear against adjacent splits, shifting said split-rod carriage away from said reed, shifting the reed vertically to carry the hooked ends beyond the unhooked ends to form a shed between the odd numbered and even numbered sheets, inserting a leasing element in the shed, returning the reed to its normal position, shifting the split-rod carriage to a position adjacent the reed, repeating the operations recited above to form a second shed between the odd numbered and even numbered sheets in reverse order, and inserting a leasing element in the second shed so formed.

SIMPSON JAMES ADAMS.
